DESIGN FOR A UNIFORM DRESS

Lydia Mead, New York, N. Y.

Application April 17, 1941, Serial No. 100,472

Term of patent 14 years

To all whom it may concern:

Be it known that I, Lydia Mead, a citizen of the United States, residing at New York, in the county of New York and State of New York, have invented a new, original, and ornamental Design for a Uniform Dress, of which the following is a specification, reference being had to the accompanying drawing, forming part thereof wherein:

Fig. 1 is a front perspective view of a uniform dress showing my design, and

Fig. 2 is a rear perspective view of the uniform dress shown in Fig. 1.

I claim:

The ornamental design for a uniform dress, substantially as shown.

LYDIA MEAD.
